United States Patent Office

Des. 182,511
Patented Apr. 15, 1958

182,511

JEWEL BOX

William H. Hardy, River Edge, N. J.

Application October 28, 1957, Serial No. 48,258

Term of patent 3½ years

(Cl. D86—9)

FIG. 1

FIG. 4

FIG. 2

FIG. 3

FIG. 5

Fig. 1 is a top plan view of a jewel box showing my new design.

Fig. 2 is a front view thereof;

Fig. 3 is a side view thereof;

Fig. 4 is a rear view thereof, and

Fig. 5 is an open view thereof.

I claim:

The ornamental design for a jewel box, substantially as shown.
